DOWEL BAR DEVICE

Filed April 4, 1930

UNITED STATES PATENT OFFICE

WILLIAM C. BURRELL, OF KANKAKEE, ILLINOIS, ASSIGNOR OF ONE-HALF TO ROBERT R. ROBERTSON, OF CHICAGO HEIGHTS, ILLINOIS

DOWEL BAR DEVICE

Application filed April 4, 1930. Serial No. 441,475.

In the construction of reinforced concrete roads and the like, it has been found necessary to provide metallic center strips which are usually supported in position by means 5 of retaining pins or stakes and have dowel bars which project through apertures in the center strip and have the ends thereof supported by means of dowel bar supporting pins.

10 Heretofore, dowel bars have usually been constructed of solid rods or bars which require the ends thereof to be supported by means of separate supporting pins or stakes which are driven into the sub-grade to permit the ends of the dowel bars to be projected 15 through apertures in the pins. To eliminate the use of solid metal dowel bars and the requirement of separate dowel bar supporting pins or stakes, and to provide an increased thickness of material where the dowel bars project through the center strip, this invention has been devised for the purpose of 20 providing an improved combination dowel bar and supporting pin of unitary construction, constructed of grooved or channeled metallic material to provide a dowel bar device adapted to be constructed of light-weight material and grooved or channeled to 25 increase the surface area thereof to provide a greater contact surface with the concrete and furthermore adapted to receive quantities of the concrete embedded in the grooves or channels thereof to provide a rigid reinforcement for the concrete body section of 30 the road as well as a suitable support for a road center strip, said dowel bar devices adapted to be used in overlapping or interfitting pairs arranged to have the interfitting 35 ends disposed to project through a center strip opening to afford a double or increased thickness of dowel bar material at the point of intersection of the dowel bars with the center strip.

40 It is an object of this invention to provide an improved dowel bar device of channeled or grooved construction to afford increased contact surface with concrete and furthermore adapted to receive a quantity of the 45 concrete seated therein to provide a tight fit 50

between the dowel bar and the concrete in which the dowel bar is embedded.

It is also an object of this invention to provide an improved channel dowel bar having a dowel bar supporting pin integrally formed 55 on one end thereof, and adapted to be used with a similar dowel bar to interfit the same and afford an increased thickness of material where the interfitting dowel bars project through a center strip. 60

It is a further object of this invention to provide a dowel bar device for concrete road construction and the like, said device consisting of interfitting channel dowel bar sections 65 adapted to project through an apertured center strip at the point of intersection of said dowel bar sections to increase the thickness of the dowel bar metal at the point of intersection with the center strip. 70

It is furthermore an object of this invention to provide an improved dowel bar device constructed of a dowel bar section of increased thickness intermediate its ends and having dowel bar supporting pins or stakes secured on the outer ends thereof to facilitate mounting of the dowel bar device. 75

It is an important object of this invention to provide an improved type of dowel bar device adapted for concrete road construction work and the like, said dowel bar device 80 being constructed of channel metal formed to provide a channel dowel bar section with a section of increased thickness of metal and having channel-shaped dowel bar supporting pins integrally formed on the ends thereof and provided with tapered ends and with wing flanges to facilitate engagement of the pins in a road sub-grade up to a required depth, depending upon the position of said wing flanges. 85 90

Other and further important objects of this invention will be apparent from the disclosures in the specification and accompanying drawing.

This invention (in a preferred form) is 95 illustrated in the drawing and hereinafter more fully described.

On the drawing:

Figure 1 is a fragmentary perspective view 100 of a section of a concrete road having an

bedded therein a center strip supported in place by means of a retaining pin or stake and having engaged therethrough improved interfitting combination dowel bars of channel construction having dowel bar supporting pins or stakes integrally formed on the ends thereof and embodying the principles of this invention.

Figure 2 is a fragmentary perspective view 10 of one of the improved dowel bar devices constructed of angular channel material.

Figure 3 is an end elevation of the dowel bar device illustrated in Figure 2.

Figure 4 is a fragmentary perspective view 15 of a portion of a modified form of dowel bar device of a construction similar to that illustrated in Figure 2, but constructed of half round channel material.

As shown on the drawing:

20 The reference numeral 1 indicates a concrete road sub-grade having formed thereon a concrete crown or top section 2, in which a metal center strip 3 is embedded, with the lower longitudinal margin or edge of said center strip resting upon the sub-grade 1. The center strip is provided with an intermediate trough or V-cross-sectioned middle section 4 which is provided with a pair of openings or apertures 5 which are disposed 25 in each of the walls of the middle section 4 and are axially aligned with one another for the reception of a channel-cross-sectioned metal retaining pin or stake 6, the lower end of which is tapered at 7 to permit the same 30 to be conveniently driven into the sub-grade 1 for the purpose of supporting the center strip in a vertical position along the center line of the road. The lower edge of the center strip 3 rests on the sub-grade 1, while 35 the upper longitudinal edge of said center strip is positioned a short distance below the eventual top surface or level of the crown section of the concrete road.

40 Mounted on the upper longitudinal edge of the center strip 3 is a removable mold strip or cap 8 having integrally formed on the lower longitudinal edge thereof a plurality of tongues or flaps 9 which are separated by notches or spaces to permit the tongues to be 45 engaged in staggered relation on opposite sides of the top margin of the center strip.

50 The grooved middle section 4 of the center strip is also provided with an opening or aperture 10 which is located in the middle or angled portion of the intermediate section 4 and is provided for the reception of one or more dowel bars.

55 The dowel bar device embodying the principles of this invention is illustrated in detail in Figures 2 and 3 and comprises a channel-cross-sectioned or grooved dowel bar section 11 adapted to be constructed of a metal channel bar or of sheet metal. Integrally formed on one end of the dowel bar 60 section 11 is a channel-cross-sectioned or

grooved dowel bar supporting pin or stake 12, the lower end of which is cut to provide a tapered tip or point 13 which is adapted to be driven downwardly into the sub-grade 1 a distance adapted to be limited by a pair of outwardly projecting wing flanges or arms 14 which are struck from the lower portions of the sides or flanges of the channel-cross-sectioned dowel bar pin 12.

70 In the use of the improved dowel bar device, the free end of the dowel bar section 11 is adapted to be projected through the opening 10 of the middle section 4 of the center strip, and the dowel bar supporting pin is adapted to have the point or tip 13 thereof driven into the sub-grade 1 until the stop flanges or arms 14 seat against the top surface of the sub-grade, as illustrated in Figure 1. A second dowel bar device is used on the opposite side of the center strip, and the free end of the dowel bar section 11 of the second device is adapted to be slightly pinched, as indicated at 15, to restrict or compress the end of the dowel bar section so that the same 75 may be frictionally engaged or pushed into the free end of the opposite dowel bar device. The dowel bar supporting pin of the second device may then be driven downwardly into the sub-grade similar to the positioning of the dowel bar device supporting pin shown in full lines in Figure 1. This arrangement of the two interfitting dowel bar sections 11 provides a double thickness of metal at the points where the dowel bar sections project through the aperture 10 of a center strip, thus producing a reinforced dowel bar construction where additional strength is most needed, since it is at the intersection of dowel bars with center strips 80 that weaknesses develop due to corrosion of the dowel bar metal.

85 If preferred, the improved dowel bar devices, instead of being used in interfitting pairs as illustrated and described in connection with the showing in Figure 1 of the drawing, may be used in staggered relation 90 on opposite sides of the center strip with the respective free ends of the dowel bar sections 11 having end portions of increased thickness and projecting in opposite directions 95 through different openings provided in the center section 4 of the center strip.

100 Figure 4 of the drawing shows a fragmentary modified form of material adapted for use in constructing dowel bar devices. In this modification, a half round metal bar 16 is used and is adapted to have one end thereof bent over at right angles similar to the arrangement illustrated in Figure 2 to form a dowel bar supporting pin, the lower end of which is adapted to be tapered and have a plurality of wings or flanges struck therefrom to correspond with the flanges 14 of the dowel bar supporting pin 12 illustrated in Figures 2 and 3. The improved 105

dowel bar device is adapted to be constructed of grooved or channel material, or may be constructed from blanks or forms struck from sheet metal, said forms adapted to be 5 eventually bent into the shape corresponding to that illustrated in Figures 2 and 3 of the drawing. In cases where the channel dowel bars are used individually, one end of the channel section 16 or 11, as the case may be, 10 may be of increased thickness, which may be produced by doubling the material on itself to provide a strengthened end section 17.

It will, of course, be understood that various details of construction may be varied 15 through a wide range without departing from the principles of this invention, and it is, therefore, not purposed to limit the patent granted hereon otherwise than necessitated by the scope of the appended claims.

20 I claim as my invention:

1. A dowel bar device comprising a dowel bar section, a dowel bar supporting pin integrally supported on one end thereof, and stops formed on said pin.
- 25 2. A dowel bar device comprising a channel dowel bar section, a tapered dowel bar supporting pin secured on one end thereof, and stop flanges integrally struck from said pin to afford stops for limiting the insertion 30 of the pin into a road sub-grade.
3. A dowel bar device comprising a grooved dowel bar section, a grooved supporting pin therefor integrally formed on one end of said section, and means integrally 35 formed on said supporting pin for limiting the insertion thereof into a road sub-grade.
4. A dowel bar device comprising a dowel bar section having one end thereof deflected to provide a supporting pin, and means integrally 40 formed on the supporting pin to afford stops for limiting the insertion of the pin into a road sub-grade.
5. A dowel bar device comprising a pair of interfitting sections affording a double 45 thickness of material, means connected with the ends of said sections to support the same in position, and stop members formed on said means.
6. A dowel bar device comprising a channel 50 section having one end of increased thickness of material, and means connected with the other end for supporting the dowel bar device in position, said means having a portion thereof shaped for limiting the insertion 55 thereof into a road sub-grade.

In testimony whereof I have hereunto subscribed my name at Kankakee, Kankakee County, Illinois.

WILLIAM C. BURRELL.
